UNITED STATES PATENT OFFICE.

LEMUUEL FREDERIC HOWARD, OF EDGEWOOD PARK, PENNSYLVANIA, ASSIGNOR TO THE UNION SWITCH AND SIGNAL COMPANY, OF SWISSVALE, PENNSYLVANIA, A CORPORATION OF PENNSYLVANIA.

SOLENOID-MOTOR.

No. 899,598.

Specification of Letters Patent.

Patented Sept. 29, 1908.

Application filed October 23, 1906. Serial No. 340,136.

To all whom it may concern:-

Be it known that I, LEMUEL FREDERIC HOWARD, a citizen of the United States, residing at Edgewood Park, in the county of Allegheny and State of Pennsylvania, have invented certain new and useful Improvements in Solenoid-Motors, of which the following is a specification.

This invention relates to cushioning devices for solenoid motors, its object being to absent the momentum of moving parts without producing any considerable strain or shock on the apparatus.

The invention is applicable to solenoid motors used for various purposes and in the present case I have illustrated it in connection with a railway signal operated by a solenoid motor.

I will describe preferred embodiments of my invention and then point out the novel features in claims.

In the accompanying drawing, Figures 1 and 2 are elevations, partly in section and partly broken away, of a railway signal and a solenoid for operating it, the parts being shown in different positions in the two figures. Figs. 3 and 4 are views, similar to Figs. 1 and 2, showing a modification.

It is well known that if a coil of wire is wound so as to leave an opening through its center, as would be the case when it is wound on a tube of non-magnetic material, and a bar of iron is introduced partway into the coil and released when the coil is energized, the bar will be drawn into the coil and be carried by its inertia beyond the center of the coil. It will then be drawn back and finally come to rest in such position that its center coincides with the center of the coil, assuming both bar and coil to be symmetrical and the bar free to move in both directions. Where solenoids are employed to move parts such as a signal, it is necessary to limit the movement of the core in one direction and if a rigid stop is employed for this purpose, especially when the moving parts have considerable weight there is necessarily considerable shock and strain to the apparatus. By my invention rigid stops are dispensed with and the magnetic force of the solenoid itself is utilized to resist the inward movement of the core beyond a certain limit.

Referring now to Figs. 1 and 2, A indicates a semaphore signal of the type which normally tends to assume danger position.

B indicates the coils of a solenoid and C the yoke. The core is in two sections, *b* and *b*¹. The section *b*, which may be termed the operative section, is connected to a lever *e* and the latter is connected by a rod *d* to the part to be moved, in this case the signal A. When the coils of the solenoid are deenergized the section *b* of the core will fall by gravity to the position indicated in Fig. 1, the signal will indicate danger as shown, and there will be a space between the inner ends of the two sections of the core. The section *b* of the core has, preferably, a conical recess *x* in its inner end, and the inner end *y* of the section *b*¹ is conical to fit in the recess *x*. The advantage of this construction is that when the section *b* moves inwardly to engage the section *b*¹ an air cushion will be formed in the conical recess which will relieve the shock and prevent undue wear on the opposing ends. The section *b*¹ of the core is provided with a collar *b*² of non-magnetic material which normally rests on the yoke C and, being rigidly connected to the section *b*¹ of the core, will prevent inward movement of such section beyond its normal position.

Such being a preferred construction, the operation is as follows: When the coils are energized the section *b* will move inwardly and the section *b*¹ will have a tendency to also move inwardly, but will be prevented by its collar *b*², and consequently it will remain at rest and have a tendency to resist outward movement. As soon, therefore, as the section *b* engages *b*¹ the latter will resist further inward movement of the former, but the inertia of *b* added to the magnetic forces acting on it will be sufficient to overcome the resistance of *b*¹ and since the latter is free to move outwardly the sections *b* and *b*¹ will move together for a short distance as indicated in Fig. 2, and the resistance offered by *b*¹ to the movement of *b* will not cause any appreciable shock or strain to the apparatus. As soon as the upward movement of the two sections ceases they will move back together until the collar *b*² rests on the yoke C and will remain in such position until the coils are deenergized when the section *b* will drop away from *b*¹ to the position shown in Fig. 1. The inward movement of section *b* moves the signal to safety position.

Referring now to Figs. 3 and 4, the parts are the same as in Figs. 1 and 2, with the exception that the section *b*¹ is centrally bored

to receive a pin b^3 of magnetic material. This pin is free to slide in the section b^1 and its inward movement is limited by a head b^4 . The inner end of the pin b^3 projects into the space normally existing between the inner ends of the sections b and b^1 of the core. When the coils are energized the pin b^3 will also have a tendency to move inwardly but as it is prevented by the head b^4 from having this movement it will remain at rest with a tendency to resist outward movement. During the inward movement of the section b the latter will first come in contact with the pin b^3 and the resistance offered by the latter will tend to lessen the force of contact between b and b^1 and thus render the pull of the core on the lever more uniform. The section b^1 will also resist the movement of b as already described.

20 It will thus be seen that the magnetic forces of the solenoid are utilized to cushion the inward movement of the core and that very little shock or strain will occur when the moving parts are stopped.

25 Without limiting myself to the precise details of construction illustrated and described, I claim:

1. A solenoid motor having a core comprising two sections normally tending to move inwardly in opposite directions, one of said sections having a conical inner end and the other a conical recess in its inner end to

receive said conical end, and one of said sections being free and unobstructed to move outwardly when engaged by the other section on its inward movement but provided with means for limiting its inward movement under the influence of magnetic forces of the coils. 35

2. A solenoid motor having a core comprising two sections normally separated when the coils of the solenoid are deenergized, and normally tending to move inwardly in opposite directions when said coils are energized, means for limiting the inward movement of one section under the influence of magnetic forces, and said last named section being centrally bored, a pin extending through said bore into the space normally existing between said sections, and means for limiting the inward movement of said pin under the influence of magnetic forces, and both the pin and the section through which it extends being movable outwardly when engaged by the other section on its inward movement. 45 50 55

In testimony whereof I have signed my name to this specification in the presence of two subscribed witnesses.

LEMUEL FREDERIC HOWARD.
